UNITED STATES PATENT OFFICE.

JOSEF SPERLICH, OF ORLAND, CALIFORNIA.

ICE-SCRAPING DEVICE.

Application filed October 29, 1924. Serial No. 746,669.

To all whom it may concern:

Be it known that I, JOSEF SPERLICH, a citizen of the United States of America, residing at Orland, county of Glenn, State of California, have invented certain new and useful Improvements in Ice-Scraping Devices; and I do hereby declare that the following is a full, clear, concise, and exact description of the invention, such as will enable others skilled in the art to which it appertains to make and use the same.

This invention relates to improvements in ice scraping devices, having for an object to provide an ice scraper constructed with a novel form of casing, the cover of which, in addition to serving its normal utility, may be advantageously employed as a scoop or spoon with which the scraped ice, or a portion thereof, may be conveniently removed from the casing, as required.

Another and equally important object of the invention is to provide the scraper with a novel mounting for the scraping blade thereof, the same being arranged in a position upon the casing whereby pressure may be directly applied thereto in order that an amount of ice may be scraped in a minimum time and being capable of adjustment, in order that the fineness or grade of the scraped ice may be regulated and the casing may be loaded in greater or less time.

Other objects of the invention will be in part obvious, and in part pointed out hereinafter.

In order that the invention and its mode of operation may be readily understood by persons skilled in the art, I have in the accompanying illustrative drawings, and in the detailed following description based thereupon, set out one possible embodiment of the same.

In these drawings:—

Figure 1 is a perspective view of the improved scraping device scraper;

Figure 2 is a vertical longitudinal section through the same;

Figure 3 is a similar view having one portion thereof shown in elevation and the cover arranged upon the casing as when the same is used as a scoop or spoon for removing the scraped ice or a portion thereof from such casing; and,

Figure 4 is an end elevation of the improved scraper having a portion thereof broken away and shown in section.

Having more particular reference to the

drawings, in connection with which like characters of reference will designate corresponding parts throughout, the improved device may be stated to comprise a substantially rectangularly shaped casing generally indicated herein by the numeral 1, a heel or hand engaging portion or shoulder 2 being formed upon the upper and rearward end of said casing 1, as is clearly shown in the Figure 2, while a pocket or seat is formed in the rearward end wall of said casing directly below the heel or shoulder 2 and is adapted to receive a scraping blade 3 therein, said scraping blade being formed with an intermediately arranged slot 4 through which the shank portion of a securing bolt 5 is adapted to pass; said bolt being passed through an opening formed in an adjacent portion of the rearward end wall of the casing 1 and having its head arranged within the casing as is clearly shown in the Figure 2. A clamping or securing plate 6, substantially square in shape, and formed with a concentrically arranged opening is then engaged over the free or extended shank portion of the bolt 5 and over the adjacent portion of the blade 3, whereupon a wing nut or similar locking device 7 is turned into engagement with the screw threaded portion of said bolt shank 5 whereby to clampingly engage the scraping blade 3 between the rearward end wall of the casing 1 and said clamping plate 6.

It is to be noted at this point that the scraping blade 3 is provided, upon its opposite marginal portion, with several different forms of cutting edges, indicated for the purpose of convenience, by the numerals 8 and 9, the cutting edge 8 being of regular or knife-like formation, while the cutting edge 9 is of irregular or serrated or toothed formation as is clearly shown. Thus, it will be readily understood that by reversing the positioning of this cutting blade 3 in its pocket in the rearward end wall of the casing 1, the fineness of ice to be shaved from a block may be regulated to the desired nicety and furthermore, that the loading of the casing 1 of the ice scraper may be accomplished in greater or less time, as may be required.

A transversely disposed opening, indicated by the numeral 10 is formed in the bottom of the casing 1 adjacent the arrangement of the cutting blade 3 upon the rearward wall thereof and as will be noted, the partie-

ular cutting edge of said blade being employed, projects for a distance below the bottom of the casing 1. Adjustment of the cutting blade 3 with respect to the rearward 5 end wall of the casing 1 receiving the same and with respect to the bottom of said casing 1 may be readily effected merely by loosening the wing nut 7 and in consequence, permitting sliding movement of said cutting 10 blade by reason of the slot 4 formed therein over the adjacent shank portion of the securing bolt 5. With proper adjustment of the lowermost or exposed cutting edge of the blade 3, the wing nut 7 is then tightened 15 upon the securing bolt 5 whereby to rigidly secure the blade with respect to the casing 1.

With a view towards providing means for covering the open top and one end wall of the casing 1, whose construction is more 20 clearly shown in the Figure 3, a cover 11 is provided the device, the same being of angular formation and having the portion 12 thereof of a width to overlappingly engage the adjacent marginal portions of the 25 open end of the casing 1, as is shown in the Figure 1. The upper or outer portion of this cover 11 is constructed of a width such as to permit of its snug reception between the opposite walls of the open upper portion 30 of the casing 1 and to support said cover in such position with respect to the casing 1, laterally extending headed bearing pintles or pins 13 are formed upon the opposite sides and intermediate portions of 35 said upper or outer portion of the cover 11 and are removably received in pockets or recesses 14 formed in the adjacent upper portions of the side walls of said casing 1.

The cover 11, at times, is adapted to serve 40 as an efficient form of scoop or spoon for use in removing the scraped ice or a portion thereof from the casing 1 and to facilitate such usage of said cover, a right angularly disposed flange or lip 15 is formed upon the 45 free end of the upper or outer portion of said cover 11 as is shown in the Figures 2 and 3. The outer side of this flange or lip 15 is bevelled, as at 16, in order that the same, with usage of the cover as a scoop or 50 spoon, will flushly contact with the bottom of the casing 1 as is clearly shown in the Figure 3, thereby effectually removing the scraped ice or a portion of the same, as may be required.

55 Due to the width of the upper or outer portion of the cover 11, it will be understood that when the same is employed as a scoop or spoon, its snug transversal engagement in and passage through the casing 1 will be 60 permitted in order that the scraped ice or a portion thereof may be readily removed. When the cover is used for its normal purpose, the flattened or straight-edged portion of the flange 15 in abutting the adjacent 65 correspondingly formed side of the shoulder

2 will provide an effectual stop for the free end of the upper or outer portion of the cover 11 and in consequence, will prevent its movement, pivotally, upon the pin 14 downwardly into said casing 1 and hence, will 70 avoid interference during an ice shaving operation. Furthermore, by reason of the overlapping engagement of the curved portion 12 of the cover 11, with respect to the open end of the casing 1, it will be understood 75 that downward movement of said part of the cover with respect to the open end wall of the casing 1 will be positively prevented irrespective of that pressure applied to the same during an ice shaving operation. 80 Hence, the cover 11 is positioned with reasonable rigidity in the casing 1 during the shaving of ice therewith.

The mounting of the scraping blade 3 in the pocket formed in the outer side of the 85 rearward end wall of the casing 1 is such as to positively prevent any attempt at lateral movement of said blade and with proper tightening of the wing nut 7 upon the securing bolt 5 and the resultant engagement of 90 the clamping plate 6 with said blade 3, the same will be securely retained in an adjusted position with respect to the bottom of the casing 1.

As aforesaid, the positioning of the scraping blade 3 may be reversed so as to optionally engage either the cutting edge 8 or the cutting edge 9 with the ice block from which a quantity of ice is to be scraped or shaved. This particular feature of the device is found to be especially advantageous. For example, when it is desired to quickly load the casing 1 of the scraper with scraped ice, the serrated or toothed cutting edge 9 of the scraping blade 3 is arranged 100 adjacent or in proximity to the bottom of such casing, whereupon with its movement under pressure over a block of ice, the same will function to quickly load said casing 1 with scraped ice. Where it is desired to use finely graded ice from the casing 1, the positioning of the scraping blade 3 is then such as to bring the cutting edge 8 in position adjacent the bottom of the casing 1, whereupon the removal of ice from the block will be more by process of shaving and in consequence, will avoid the presence of large particles of ice in the contents of the casing 1.

Manifestly, the construction shown is capable of considerable modification, and such modification as is within the scope of my claims, I consider within the spirit of my invention.

I claim:

1. An ice scraper comprising in combination with a casing having the top and one end thereof open, a cover of angular formation therefor, said cover being removable from the casing, and a flange upon one end

of the cover adapted to flushly contact with the bottom of such casing, at times.

2. An ice scraper comprising in combination with a casing having the top and one end thereof open, a cover of angular formation therefor, one portion of said cover being of a width to permit of its snug transversal reception in the casing and movement therethrough, at times, and a flange upon 10 one end of the cover adapted to flushly contact with the bottom of said casing, at times.

3. An ice scraper comprising in combination with a casing having the top and one 15 end thereof open, a cover of angular formation therefor, said cover being removable from the casing and having one portion thereof of a width to permit of its snug transverse reception and movement through 20 the casing.

4. An ice scraper comprising in combination with a casing having the top and one end thereof open, a cover of angular formation therefor, said cover having one portion 25 of the same formed of a width to overlappingly engage with the adjacent portions of the open end of the casing and the remaining portion thereof formed with a width to permit of its snug transversal reception in and movement through the casing.

5. An ice scraper comprising in combination with a casing having the top and one end thereof open, a cover of angular formation therefor, one portion of said cover being of a width to permit of its overlappingly engagement with the adjacent portions 35 of said open end of the casing and its re-

maining portion formed of a width to permit of its snug transversal reception in and movement through the casing, and a flange formed upon the free end of said remaining portion of the cover adapted to flushly contact with the bottom of the casing, at times.

6. An ice scraper comprising in combination with a casing having a pocket formed in the outer side of the rearward wall thereof, a scraping blade snugly received in said pocket and adapted to have movement 50 through the same, one portion of said blade being positioned in proximity to the bottom of the casing and adjacent the transverse opening formed therein, and means for adjustably securing said scraping blade 55 in position adjacent said rearward and end wall of the casing.

7. An ice scraper comprising in combination with a casing having a pocket formed in the outer side of the rearward and end wall thereof, a shoulder formed upon the upper portion of said rear wall, a scraping blade snugly receivable in said pocket, said blade having cutting edges of different characters formed upon its opposite portions, means for adjustably and clampingly retaining said scraping blades in the pocket upon said rearward and end wall, the lower portion of the scraping blade being adapted 60 for arrangement in proximity to the bottom 65 of the casing and adjacent the transverse opening formed therein.

In witness whereof I have hereunto set my hand.

JOSEF SPERLICH.
